UNITED STATES PATENT OFFICE.

EUGÈNE SCHNEIDER, OF PARIS, FRANCE, ASSIGNOR TO SCHNEIDER & CIE, OF PARIS, FRANCE, A LIMITED JOINT STOCK COMPANY OF FRANCE.

APPARATUS FOR APPLYING CORRECTIONS IN THE LAYING OF ARTILLERY PIECES FROM A DISTANCE.

Application filed June 30, 1923. Serial No. 648,832.

To all whom it may concern:

Be it known that I, EUGÈNE SCHNEIDER, a citizen of the Republic of France, resident of Paris, France, have invented new and useful Improvements in Apparatus for Applying Corrections in the Laying of Artillery Pieces from a Distance, which is fully set forth in the following specification.

In the laying of guns from a distance, the object is to permit a single gun-layer to control a group of pieces.

This gun layer generally uses a special telescope mounted on a dummy gun called a "distant controller," but alternatively he may use a sighting apparatus of one of the pieces of the group.

The pieces are oriented by gun servers to correspond with the indications that they receive from the distant controller station, through the medium of suitable transmissions.

The firing of these pieces is generally effected by the closing of an electric interrupter which is placed at the distant control station and is operated at the moment when the image of the target passes on to the hair line of the elevating telescope installed at that station.

It is clearly evident that even in the theoretical case where all the pieces are identical among themselves, and where all the platforms are situated in the same horizontal plane, the points of fall of the projectile, if the pieces were parallel among themselves, would still be different and their distribution in plan would theoretically be a reproduction of that of the pieces. In order to cause these points of fall to converge on to the target, it is therefore necessary to first of all correct the training of the pieces by introducing a correction in order to take account of parallax.

In practice the pieces will not generally be at the same altitude; they will not be at the same distance from the target, they will not be exactly identical among themselves, and they will not impart to the projectile the same initial speed, and finally their platforms will not be parallel. It will then be necessary to correct the elevation of the pieces and to apply thereto the following corrections:

Correction for parallax in order to take account of the differences of altitude; cor-

rection for difference of distance from the target; correction for the initial speed of the projectile; and correction for the inclination of the platform.

In the case of firing on board warships, in order that the gun laying may be correct, it is further necessary to take account of the inclination of the deck with reference to the plane of fire, and the speed with which the piece is displaced vertically by the movements of the ship. Apparatus for effecting these two latter corrections are described in the French patents of the 12th March 1921 and of the 15th June 1921 and will not be referred to in the following description.

The invention consists in an installation for mechanically solving the formulæ which give the corrections hereabove set forth, and for correcting the laying of the artillery pieces by the introduction of the said corrections.

By way of example there will hereinafter be described how the invention may be applied to the artillery of a warship.

Correction for parallax in azimuth.—According to the invention, all the pieces of the same calibre belonging to the same broadside, and whose distance apart counted along the direction of the axis of the ship is less than a given limit, will be grouped in such a way as to constitute a certain number of sections and the corrections for parallax will be determined at the distant controller for imaginary pieces, which are assumed to be situated as near as possible to the centre of each section and to be placed on a straight line which passes through the horizontal projection of the distant controller. This solution evidently allows small errors in azimuth to remain uncorrected (these small errors may always be made less than a predetermined limiting value), but it has on the contrary the very great advantage of allowing the determination of the correction at the distant controller itself, and in remarkably simple conditions.

If, in fact the target is indicated by B (see the diagram of Fig. 1), the distant controller by T, the pieces of the same broadside assumed to be grouped in three sections by C₁, C₂, C₃, C₄, C₅, C₆, C₇, C₈, and the three imaginary pieces for which the parallax at T is to be determined by

S_1, S_2, S_3 , then the corrections for parallax p_1, p_2, p_3 to be applied to the pieces of each of the three sections are given by the formulæ:—

$$5 \quad \sin p_1 = \frac{TS_1}{D_1} \sin a$$

$$10 \quad \sin p_2 = \frac{TS_2}{D_2} \sin a$$

$$15 \quad \sin p_3 = \frac{TS_3}{D_3} \sin a$$

in which D_1, D_2, D_3 respectively indicate the distances from the target of the imaginary pieces S_1, S_2, S_3 , and a indicates the angle which the line of sight TB makes with the straight line S_1, S_2, TS_3 .

As the distances D_1, D_2, D_3 are always in practice sufficiently close to the distance D of the distant controller T from the target, and as also the angles of parallax are always so small that they may be substituted for their sines, therefore the above formulæ 25 may be replaced by the following:—

$$p_1 = \frac{TS_1}{D} \sin a$$

$$30 \quad p_2 = \frac{TS_2}{D} \sin a$$

$$p_3 = \frac{TS_3}{D} \sin a$$

35 and in this form they are adapted to be solved by the use of the apparatus represented diagrammatically by Figure 2.

In this figure:—1 indicates a cylindrical drum which turns as a function of a around its axis 2 and carries a graph constituted by a series of sinusoidal curves. These sinusoidal curves are graduated to correspond with the different values of D , and are obtained by taking a as abscissæ and 45 for ordinates the values of the function

$$\frac{\sin a}{D}$$

3 is a handle for turning the screw 4; 50 while 5 is a nut which is mounted on 4 and carries a fork 6 in which is engaged the fixed rod 7, so that when 3 is caused to turn, the nut 5 is displaced along 4. An index 8 is fixed to 5 and this index is displaced 55 to correspond with one of the generatrices of 1; 9—10, 12—13, 15—16 are three series of pairs of bevel wheels which when the screw 4 makes one turn, respectively impart TS_1 turns to the shaft 11, TS_2 turns 60 to the shaft 14, and TS_3 turns to the shaft 17.

It is clear that in order to bring the index 8 from the righthand extremity of the cylinder up to the curve corresponding to the 65 distance D , it will be necessary to turn the

screw 4 through a number of turns proportional to

$$\frac{\sin a}{D}$$

70 and that accordingly the number of turns made by the shafts 11, 14, and 17 will be respectively proportional to p_1, p_2 and p_3 .

The corrections thus determined will be introduced into the transmission of the bearing given by the shaft g , by means of differentials such as d_1, d_2, d_3 interposed between this shaft and the transmitters t_1, t_2, t_3 .

75 In Figure 2 it should be noted that there is also a second index 18, which is fixed at 19 to a steel band 20. One of the extremities of this steel band 20 is constantly subjected to a pull from a barrel 21, (in the direction indicated by the arrow), while the other extremity is wound on a pulley 22 rigidly connected to the pinion 23 which gears with the rack 24. When the index 18 reaches the righthand extremity of the drum 1, its displacement is stopped by the fixed stop 25. The index 18 is on the other hand drawn along towards the left from the time when the movable stop 26, carried by the nut 5 in the same direction, comes to strike the rack 24; and this index 18 then reproduces all the displacements of 8 with a multiplication equal to the ratio r of the diameter of 22 to the diameter of 23. Thus when the index 8 approaches the 90 left of the drum, in which neighbourhood 100 the traces of the first sinusoidal curves are more or less closed up towards one another, then instead of and in place of 8, there may be used the second index 18, on condition that the readings are made on a second 105 graph set up by adopting for ordinates a scale which is r times as great as the scale for the first graph and this device will considerably facilitate the readings. In order to make the outlines of the graphs more 110 convenient, the stops 25 and 26 will be set in such a way as to permit the use of the same curves for both graphs. These curves will then carry two graduations, and in order to avoid any confusion, these graduations (and the corresponding indexes) will 115 be distinguished by different colours.

120 *Correction for parallax in altitude.*—In the same way as for the parallax in azimuth, all the pieces of the same calibre which are at the same level will be grouped together. If H denotes the difference of level between the distant controller and the horizontal plane which corresponds to the mean altitude of a section, then the correction i_1 to 125 apply to the elevation of the pieces of the said section is given by the formula

$$i_1 = \text{arc tan } \frac{H}{D}$$

As has already been stated, the distant controller comprises a sighting apparatus which is identical with those usually found on guns. If this sighting apparatus comprises a cam to allow of suitably orienting the telescope with reference to the axis of the piece in function of the distance D , then the contour of this cam may be corrected in such a way as to take account of the correction i_1 in the elevating of the telescope.

In the most general case where the sighting apparatus will not comprise any cam for the elevation of the telescope, then a cam will be introduced into the mechanism for the actuation of the telescope, said cam being driven as a function of the distance D and being specially adapted to take account of the correction i_1 .

Correction for the inclination of the platform.—It will be of interest to measure the inclination b of the platform of each piece, not directly with reference to the platform of the distant controller, but with reference to an intermediate plane comprised between the two most inclined platforms. It will thus be necessary to apply to the distant controller itself a correction for the inclination of its platform, but thereby the importance of the individual corrections will be considerably reduced, which will simplify the construction of the apparatus.

If g_0 denotes the bearing of the line of greatest slope and b the inclination of the platform of one of the pieces, then the correction i_2 to apply to the elevation of this piece will be given by the formula

$$i_2 = b \cos(g - g_0).$$

Figure 3 diagrammatically represents an apparatus for the mechanical determination of this correction and for its introduction in the transmission of the elevation. In this figure, 101—102 is a shaft which turns proportionally to the bearing g ; 103—104 is a plate keyed on 101—102; 105—106 is a plate which can be made rigid with 103—104 by clamping the screw 107 when brought into a position such that the section by the plane of the paper in Figure 3 corresponds to the graduation g_0 read on 103—104; 108—109 is a plate which may be turned round the axle 110 in the bearings 111 carried by 105—106. By acting on the screw 112 which gears with the toothed arc 113 the plate 108—109 can be inclined with reference to the shaft 101—102 through an angle proportional to $b + 90^\circ$; 114 is a roller mounted at the extremity of the screw 115. This screw 115 is thereby displaced proportionally to i_2 and is used as a rack in order to turn a pinion 46, which through 47 and 48 drives one of the pinions 49 of a differential in which the second pinion 50 is driven proportionally to the angle of inclination i of

the piece. It therefore follows that the index 52 driven by the planet wheels of the differential will be displaced proportionally to $i + i_2$. The index 52 is assumed to be mounted concentrically to the index of the receiver actuated through the distant controller, and it will be seen that when this index 52 has been brought into agreement with the latter index at the receiver, the artillery piece will in fact have been displaced through the angle $i - i_2$.

Correction for the difference in distance of the pieces from the target.—If g_1 denotes the bearing of a piece with reference to the distant controller, and l the distance between the projection of this piece, and that of the distant controller, then the difference d_3 in the distance from the target for which this correction should be calculated is equal to $1 \cos(g - g_1)$. The corresponding correction i_3 is a function of d_3 and of D , and this function can be determined exactly and introduced automatically by utilizing for example a camoid 53, which turns in function of g and is displaced along its axis in function of D . The whole of the plates 103—104, 105—106, 108—109 are made to rest on this camoid 53 through the medium of a pivot 54.

Correction for initial speed.—The correction corresponding to a variation of the initial speed V_0 of the projectile is the function on the one hand of this variation of speed, and on the other hand of the distance D . The initial speed V_0 of the projectile may be affected by different causes and specially by the power of the powder used and by the state of wear of each piece.

The first of these causes produces its effect on the whole of the pieces, and accordingly the corresponding correction may be introduced at the distant control station, by interposing a camoid in the mechanism for the control of the telescope, said camoid turning in function of D and being adapted to be displaced along its shaft as a function of this variation of V_0 .

The second cause produces an error which it is necessary to correct on each piece. This correction i_4 may be effected automatically by utilizing for example a camoid 55 which turns in function of D and is adapted to be displaced along its shaft in function of the variation of V_0 due to wear. This camoid is used in order to turn the screw 115 through the rack 56 (which is pressed against 55 by the spring 57) and through the pinions 58, 59 and 60. The screw 115 will then be mounted between a rotary connection 61 which will transmit all the displacements of the roller 114, and a longitudinally sliding connection 62 which will transmit the rotations caused by the camoid 55.

By means of the arrangement represented

in Fig. 3 it is proposed to effect the whole of the corrections $i_1 + i_2 + i_3 + i_4$ in an entirely automatic manner. As an alternative, Fig. 4 indicates a semi-automatic arrangement which can be utilized in the case where the automatically determined corrections are introduced into the transmissions through the intervention of a gun server. In this figure, 63, 64 denotes a shaft turning in function of the bearing g and driving a graph-carrying drum 65; 66 denotes a handle for turning the screw 67; 68 is a nut which is mounted on 67 and carries a fork 69 in which engages a fixed rod 70, so that when 66 is caused to turn, the nut 68 is displaced along 67: an index 71 is fixed to 68 and is displaced in front of one of the generatrices of 65. The graph should be traced for determined values of the three parameters g_0 , l , and V_0 , and accordingly it should be replaced in the case when the initial speed V_0 is modified by the wear of the piece. In these conditions, the four corrections i_1 , i_2 , i_3 , i_4 , being functions only of the bearing and of the distance, it will be understood that a graph may be traced constituted by a series of curves which are graduated in D and are obtained by taking as abscissæ g and as ordinates the values of the entire correction $i_1 + i_2 + i_3 + i_4$. It will be seen that when the gun server has displaced the index 71 in order to bring it from the middle of the drum up to the curve corresponding to the distance D , then the shaft 67 will rotate through a number of turns proportional to the entire correction that it is necessary to introduce in the transmission. This introduction can moreover be made just as has been previously explained (see Fig. 3) by utilizing a differential 49—50 in order to actuate the index 52.

Having now particularly described and ascertained the nature of my said invention and in what manner the same is to be performed, I declare that what I claim is:

1. In an apparatus for determining and introducing corrections into the angles of train and elevation transmitted to a plurality of guns to be controlled in order to insure convergence of fire, the combination, with a plurality of guns arranged in a plurality of groups, of a distant control, and mechanical means for determining the corrections to be introduced for parallax in azimuth and altitude, for inclination of the gun platform and control mechanism platform, for difference in distance of the guns and control mechanism from the target, and for differences of muzzle velocities.

2. In an apparatus for insuring convergence of fire of a plurality of guns, the combination with a control mechanism and a plurality of guns arranged in a plurality of groups, of mechanical means for determin-

ing the corrections to be introduced into the angles of train and elevation of said control mechanism and guns for parallax in azimuth and altitude, for inclination of the gun platform and control mechanism platform, for differences in distance of the guns and control mechanism from a target, and for differences of muzzle velocities of said guns.

3. An apparatus for insuring convergence of the fire of a plurality of guns comprising, in combination with a distant control, a plurality of guns, and transmitting mechanism interposed between said gun and control, means for mechanically determining and introducing into the range and training angles transmitted corrections for parallax in azimuth and altitude, differences in the inclinations of the platforms, differences in distances of said guns and control relative to a target, and for differences of muzzle velocities of said guns.

4. An apparatus for insuring convergence of the fire of a plurality of guns comprising in combination with a distant control, a plurality of guns, and transmitting mechanism for indicating gun laying angles interposed between said guns and control, means for determining and introducing into the transmitted angles of elevation and train corrections that are functions of the bearing and distance of a target from said guns and control, said means including a graph-carrying drum, a pointer associated with said drum, an index, and a differential for transmitting movements of said pointer to said index.

5. An apparatus of the type described comprising, in combination with a plurality of guns and a distant control, means for mechanically determining and introducing into the gun laying angles transmitted by said control corrections for parallax in azimuth of said guns and control, means for introducing corrections for parallax in altitude, means for determining and introducing corrections for the inclinations of the platforms of said guns and control, means for introducing corrections for the differences in distance of the guns from a firing objective, and means for introducing corrections for differences in muzzle velocities of said guns.

6. An apparatus of the type described comprising, in combination with a plurality of groups of guns and a distant control, means for mechanically introducing into the gun laying angles transmitted by said control corrections for parallax in azimuth and corrections for parallax in altitude, said corrections being determined relative to said control and a plurality of imaginary guns located substantially at the center of each group of guns.

7. An apparatus of the type described comprising, in combination, a plurality of

guns arranged in a plurality of groups, a distant control, means for transmitting gun laying angles from said control to said guns, and means for introducing into the transmitted angles corrections for parallax in azimuth and altitude.

8. An apparatus of the type described comprising, in combination, a plurality of guns arranged in a plurality of groups, a distant control, means for transmitting gun laying angles from said control to said guns, and means for mechanically introducing into the transmitted angles corrections for parallax in azimuth and altitude.

15. 9. An apparatus of the type described comprising, in combination, a plurality of guns arranged in a plurality of groups, a distant control, means for transmitting gun laying angles from said control to said guns, and means for mechanically introducing into the transmitted angles corrections for parallax in azimuth and altitude said corrections being determined with reference to said control and imaginary guns located 25 at substantially the center of each of said groups of guns.

10. Fire control apparatus for insuring convergence of fire comprising, in combination, a plurality of guns, a distant control, means for transmitting gun laying angles from said control to said guns, and means for mechanically introducing into said transmitted angles corrections for parallax, said first named means including a graph-carrying drum, a movable pointer, movable means for maintaining said pointer in indicating relation with said drum, a differential actuated by said movable means, and indicating means operatively connected to 40 said differential.

11. Fire control apparatus for insuring convergence of fire comprising, in combination, a plurality of guns, a distant control, means for transmitting gun laying angles from said control to said guns, and means for mechanically introducing into said transmitted angles corrections for parallax, in azimuth and altitude, inclinations of gun and control platforms, differences in distance of said guns and control from a firing objective, and differences in muzzle velocities of said guns, said last named means including, a rotatable drum, a graph mounted thereon, a movable pointer associated with 55 said graph, a rotatable shaft for actuating

said pointer, a differential actuated by said shaft, and indicating means actuated by said differential.

12. Fire control apparatus for insuring convergence of fire comprising, in combination, a plurality of guns, a distant control, means for transmitting gun laying angles from said control to said guns, means including a graph-carrying cylinder for mechanically introducing into said transmitted angles corrections for parallax in azimuth, a cam for introducing corrections for parallax in altitude, a movable plate for introducing corrections for inclinations of the gun and control platforms, a camoid for introducing differences in distance of said guns and control from a firing objective, and a camoid for introducing corrections for differences in muzzle velocities of said guns.

13. Ordnance apparatus comprising, in combination, a plurality of laterally displaced guns, a control therefor, means for transmitting gun laying angles from said control to said guns, means for mechanically introducing corrections into said angles for insuring convergence of fire of said guns on a target including a graph-carrying drum, a movable pointer, threaded means for moving said pointer along said drum, indicating mechanism, and a differential interposed between said mechanism and said threaded means.

14. Ordnance apparatus comprising, in combination, a plurality of laterally displaced guns, a control therefor, means for transmitting gun laying angles from said control to said guns, means for mechanically introducing corrections into said angles for insuring convergence of fire of said guns on a target including a plate, screw means for tilting said plate through an angle proportional to the angle of inclination of the platform of one of said guns plus ninety degrees, a screw having engagement with said plate, a differential actuated by said screw, and indicating means actuated by said differential.

In testimony whereof I have signed this specification.
